 namics Corporation, a corporation of New Hamp-
 shire

Filed Sept. 5, 1961, Ser. No. 135,905
 3 Claims. (Cl. 219—145)

Our invention relates to electric arc torches and relates more particularly to an improved type of electrode for use in such torches. We have developed a cathode electrode of novel construction, allowing maximum cooling without the usual difficulties associated with cooling electrodes of conventional design.

Our invention is directed to an improved electrode for use in torches shown and described in copending application Serial No. 56,221, filed September 15, 1960, by James A. Browning, now Patent No. 3,027,446, dated March 27, 1962.

Although in normal operation the anode of a high-pressure arc torch receives more heat than the cathode, the heating is generally distributed over a relatively large area of the anode surface. This is not true of the cathode surface. At the current levels now in use, the cathode arcing spot runs in a molten condition. The area of the spot is much smaller than the area of the anode in operative relationship with the arc.

To resist excessive melting, it is the usual practice to make the cathode of some highly refractory material. Since cooling of the arc spot on the cathode is essential, the material used should have as high a heat conductivity as possible. Thoriated tungsten is an excellent cathode material in that it combines a high melting point with good thermal conductivity.

It has been the usual practice to use a rather massive tungsten cylinder as the cathode electrode. Such an electrode is shown as element 11, FIGURE 1 of the Browning application referred to above. Although this arrangement is sufficient for moderate power levels, higher currents tend to cause a "spitting" of the tungsten. The erosion of the tungsten not only contaminates the plasma efflux but results in a short life for the expensive tungsten element.

The use of higher currents is made possible, in accordance with our invention, by combining a relatively small piece of tungsten with copper. The tungsten serves as the arcing surface, while the copper provides improved cooling with its high heat conductivity. We provide an electrode in which the expensive tungsten is formed in thin section and brazed, welded, or otherwise held to a copper body.

It is a principal object of our invention to provide a cathode electrode using a minimum of refractory material and a construction to facilitate cooling of the arc spot.

For a better understanding of the invention reference is now made to the drawing, in which

FIGURE 1 is a view, in section, of a disc-type cathode which is water cooled;

FIGURE 2 is a view of a cathode in which the arcing material is separated from the cooling medium;

FIGURE 3 is a variation of FIGURE 2 with a hemispherical arcing element;

FIGURE 4 is a variation of FIGURE 2;

FIGURES 5 and 6 are variations of FIGURE 1; and FIGURE 7 is another variation of FIGURE 2.

Referring now more particularly to the drawing, in FIGURE 1 a tungsten cathode disc 11 is attached to a copper tube 12 by means of a brazed joint 13. A tube 14 coaxial with tube 12 supplies water under pressure through passage 15. The water (or other suitable cool-

ing medium) strikes the back face of the thin tungsten disc 11 at high velocity and then flows out through the annular passage 16. The impinging water cools the tungsten at a point quite close to the arcing spot 17. The arc column 18 is positioned by gas, magnetic, or other means to the center of the disc 11, as shown.

The fusion temperature of tungsten is approximately 6,300 degrees F., or even higher. Thus, the molten arcing spot 17 is above that temperature. To assure that joint 13 does not fail, a sufficient distance across the disc from its center to its edge must be provided. This geometry has proven very satisfactory and allows for the use of current levels of operation which heretofore have led to excessive "spitting" and its attendant erosion. 15 Using a gas sheath vortex-flow stabilization as described in the Browning application, supra, no deleterious effects were evident at 1,000 amperes. The disc in this case was one-half inch in diameter and one-eighth of an inch thick.

20 A difficulty often encountered is cracking of the tungsten due to thermal stresses. A cracked disc will result in leakage of the cooling medium, although the disc remains satisfactory in every other way. To avoid the necessity of discarding a cracked disc, we provide a construction shown in FIGURE 2. Here a tungsten disc 11 is brazed into a shallow well formed at the end of a tube 21 by a thin integral end wall section 22. Again, joint 13 must be a sufficient distance from the center of disc 11 (the arcing spot) to avoid melting of the joint weld material. During high intensity operation, it is probable that any weld material near the center of disc 11 melts. In practice this does not affect satisfactory operation of the unit so long as a circumferentially continuous infused joint is maintained. The thin wall 22 of highly 25 conductive copper provides effective cooling (from the back) of the disc 11.

30 Other geometries within the spirit of our invention are, of course, possible. FIGURE 3 illustrates a hemispherical tungsten electrode design. The cooling of the arc spot is somewhat less effective, though the shape of the emitting element 25 may be dictated by other considerations.

35 Where the refractory material is drilled to provide a back cooling chamber, it is desirable to separate the refractory material from the coolant by a thin wall, as shown in FIGURE 4. Here a hollow tungsten piece 31 is brazed to copper element 32. Preferably, the weld material fills the entire interstice between pieces 31 and 32.

40 Whereas the embodiments thus far described have employed welded or brazed joints, we have found pressure held electrodes equally effective and, in addition, easily replaceable.

45 Such electrodes are shown in detail in FIGURES 5, 6, and 7. The pressure in each case holding the refractory material 35, 40 and 45 in place is represented by arrows 37 in each of the three figures. This pressure is supplied by assembling the torch in the manner shown in Browning copending application No. 99,403, filed March 30, 1961 now Patent No. 3,047,709 dated July 31, 1962.

50 A threaded nozzle piece, when tightened, provides the end pressure to securely seat the refractory disc against the copper tube 36 of FIGURE 5. A tapered seat provides sealing and good electrical contact between the disc 35 and the tube 36. As before, water is introduced to impinge on the back surface of the disc 35. In FIGURE 6 we show the use of an O ring 42 to effectuate a seal between the disc 40 and its holder 41.

55 Where minute cracks may develop in the refractory disc we provide a thin plate 46 as shown in FIGURE 7 to perform the same function as the thin wall 22 of FIGURE 2. When the discs are pressure held as in the

last three figures, replacement of the disc itself is easily accomplished without disturbing the copper holder or requiring the replacement of any other element. Thus in FIGURE 7, the shoulder 48 provides a resting surface for the electrode disc 45 to which the thin plate 46 may be brazed. Alternatively the three elements, disc 45, plate 46 and O ring 49 may be securely held against the end of holder 47 by pressure developed when the entire torch is assembled. It should be pointed out here that the disc of tungsten will rest, in the complete torch, against a swirl ring or other element insulating it from a nozzle which customarily serves as an anode in the non-transferred mode of operation.

While we have described preferred embodiments of our invention, other variations within the spirit and scope of the appended claims may occur to persons skilled in this art.

We claim:

1. An electrode for an electric arc torch comprising a closed tubular member of conducting material, an outer

disc shaped well at the end of said member, and a disc of refractory material nested in said well.

2. An electrode for an electric arc torch comprising an open tubular member, a shoulder formed at the end of said member and having a groove therein, a disc of refractory material adapted to fit the end of and close said member, and a sealing ring element between said disc and said member.

3. An electrode for an electric arc torch comprising an open tubular member, a shoulder formed at one end of said member and having a groove therein, a disc of refractory material adapted to fit the end of and close said member, a sealing ring in said groove, and a separate plate between said sealing ring and said disc.
